US00D406683S

United States Patent [19]

Taylor et al.

[11] Patent Number: Des. 406,683

[45] Date of Patent: **Mar. 9, 1999

[54] **OVERSIZED DROP SHOULDER CREEPER WITH T-BAR SUPPORT**[75] Inventors: **Ken Taylor**, Merced, Calif.; **Joseph J. Miles**, Plant City, Fla.[73] Assignee: **United Auto System, Inc.**, Tampa, Fla.[**] Term: **14 Years**[21] Appl. No.: **77,211**[22] Filed: **Sep. 29, 1997****Related U.S. Application Data**

[63] Continuation-in-part of Ser. No. 56,721, Jul. 8, 1996.

[51] LOC (6) Cl. .... **12-02**[52] U.S. Cl. **D34/23**

[58] Field of Search D34/12-27; 280/32.5, 280/32.6, 79.11, 79.2, 79.7

Primary Examiner—Kay H. Chin*Attorney, Agent, or Firm*—Sam Silverberg[57] **CLAIM**

The ornamental design for an oversized drop shoulder creeper with T-bar support, as shown and described.

DESCRIPTION

FIG. 1 is a top perspective view of an oversized drop shoulder creeper with T-bar Support showing our new design;

FIG. 2 is a front elevation view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1;

FIG. 8 is a right side elevational view of FIG. 1 showing a tilting headrest in a tiled position;

FIG. 9 is a top perspective view of a second embodiment of the oversized drop shoulder creeper with T-bar support;

FIG. 10 is a front elevational view of FIG. 9;

FIG. 11 is a rear elevational view of FIG. 9;

FIG. 12 is a left side elevational view of FIG. 9;

FIG. 13 is a right side elevational view of FIG. 9;

FIG. 14 is a top plan view of FIG. 9;

FIG. 15 is a bottom plan view of FIG. 9; and,

FIG. 16 is a right side elevational view of FIG. 9 showing a tilting headrest in a tilted position.
